SET OF MARKERS FOR AN EDUCATIONAL AID

Anthony C. Cozzetti, Las Vegas, Nev.
(16203 SE. 29th Place, Bellevue, Wash. 98008)

Filed May 19, 1971, Ser. No. 145,098

Term of patent 14 years

Int. Cl. D19—07

U.S. Cl. D25—1 R

The figure is a plan view of a set of markers for an educational aid showing my new design. The markers are of no appreciable thickness.

I claim:

The ornamental design for a set of markers for an educational aid, as shown and described.
